UNITED STATES PATENT OFFICE.

WILLIE A. BOYNTON, OF NEWCASTLE, TEXAS, ASSIGNOR OF ONE-HALF TO GEO. A. TERRELL, OF NEWCASTLE, TEXAS.

CLOTHES-PIN.

1,225,568.

Specification of Letters Patent. Patented May 8, 1917.

Application filed September 14, 1916. Serial No. 120,076.

To all whom it may concern:

Be it known that I, WILLIE A. BOYNTON, a citizen of the United States, residing at Newcastle, in the State of Texas, have invented a new and useful Clothes-Pin; and I do hereby declare the following to be a full, clear, and exact description of the invention, such as will enable others skilled in the art to which it appertains to make and use the same.

This invention relates to a new and useful clothes pin, and one of the objects of the invention is to provide a clothes pin having means for permanently anchoring the clothes pin to the line.

A further object of the invention is to provide a clothes pin having clamping jaws to engage the clothes on the line and clamp them in place.

20 A further object of the invention is to provide means forming a part of the anchoring means for drawing one pair of jaws toward an adjacent pair.

A further object of the invention is to 25 provide a clothes pin having two pairs of clamping jaws constructed of a single length of wire so that the adjacent parts of two pieces of clothing on a line may be engaged and clamped by the jaws, and the act of 30 moving or arranging the clothes pin to clamp the clothing will cause the jaws to pull the adjacent portions of two pieces of clothing toward each other, owing to the means carried by the anchoring means forcing 35 one pair of jaws toward the opposite pair. This drawing of the opposite parts of two pieces of clothing together stretch the clothing on the line.

In practical fields, the details of construction 40 may necessitate alterations, falling within the scope of what is claimed.

The invention comprises further features and combination of parts, as hereinafter set forth, shown in the drawings, and claimed.

45 In the drawings:—

Figure 1 is a view in perspective of the clothes pin, showing the same anchored upon the clothes line.

Fig. 2 is a view in perspective of the 50 clothes pin also anchored on the line, but showing the two pairs of jaws clamping against the line, in order to hold clothing in place.

Fig. 3 is a view in perspective showing 55 a modified construction of the clothes pin.

Fig. 4 is an edge view of the anchoring means.

Fig. 5 is a perspective view of the anchoring means.

Referring more especially to the drawings, 1 designates a clothes pin as a whole, and which is constructed of a single length of wire bent to form two spaced opposing spring coils 2. The wire beyond each coil forms opposing jaws 3 and 4. The jaws 3 of both coils incline downwardly and toward each other, and merge into the parts 5, which slightly converge downwardly and toward each other, and have their end portions bent at right angles, as shown at 6, 60 the extremities of which end portions abut. A sheet metal plate 7 is provided and which has rolls 8 and 9, which receive the lower portions of the portions 5 and said bent end portions. The portions 5 and said plate 75 constitute a suitable handle whereby the pin may be manipulated. The jaws 4 of both coils in front elevation extend downwardly and converge toward each other and merge together to form the loop 10. The 80 jaws 4 incline toward the jaws 3 for a short distance below the spring coils, and at 11 the jaws are flared downwardly, so that the loop formed by the jaws 4 is spaced apart from the portions 5, so that the clothes 85 line with the clothes thereon may be forced between the jaws 3 and 4. In Fig. 3, the bent end portions of the lower ends of the parts 5 are twisted together, as shown at 12, thereby eliminating said sheet metal 90 plate.

An anchoring member 13 is provided, and which is constructed of a piece of wire bent to form a coil 14 at one end to engage the clothes line (which may preferably be constructed of wire) and has its other end portion bent to form a pair of laterally extending loops 15, through which the portions 5 of the jaws 3 extend. It is to be seen that when the clothes pin is pulled down, causing the clothes line with the clothes thereon to be forced between the jaws 3 and 4, said laterally extending loops 15 will draw the portions 5 toward each other, thereby causing the jaws 3 and 4 to move toward the 100 other pair of jaws 3 and 4, in order to draw the adjacent portions of two pieces of clothing together, which will stretch the clothing on the line.

When the loops 15 of the anchor member 110

are near the plate 7, the depending legs 5 are not parallel but diverge from each other. Hence, when the clothes pin is pulled down over the end of two adjacent pieces that may be hanging on the line, two ends of these pieces are then drawn toward each other and the stretching referred to above is effected, it being assumed that both pieces had each been fastened at their ends remote from the clothes pin. The anchor member 13 is the means for effecting this operation, for as the depending members 5 are pulled down through its loops 15, they are moved from their diverging position into parallel relation with each other and thereby bring the jaw members closer to each other.

The invention having been set forth, what is claimed as new and useful, is:

1. A clothes pin constructed from a single piece of spring wire bent to form spaced opposing spring coils, the wire portions beyond each coil forming clamping jaws, the corresponding jaws of both pairs extending downwardly and converging toward each other and being bent and merging into downwardly extending portions, which slightly converge toward each other, said last named downwardly extending portions having means for securing them together, the other corresponding jaws of each pair extending downwardly and converging toward each other and merging together to form a loop extending outwardly and downwardly and having its free end spaced from

said last named downwardly extending portion, whereby the clothes line with the clothes thereon may be forced between two pairs of jaws, an anchoring device carried by the clothes line for connecting the clothes pin to the line, and having means for drawing said last named downwardly extending portions toward each other.

2. A clothes pin constructed from a single piece of spring wire bent to form spaced opposing spring coils, the wire portions beyond each coil forming clamping jaws, the corresponding jaws of both pairs extending downwardly and converging toward each other, one pair uniting and forming a loop flared outwardly from the other pair, the second pair having depending extensions which slightly converge and are connected by right angled bends, and an anchoring device having a loop for attachment to the clothes line and loops which engage the depending members of one pair of jaws, so that when the clothes pin is pulled over the ends of two adjacent pieces hung on the line said anchoring device will pull the two sets of jaws together and tend to stretch the pieces which it engages on the line.

In testimony whereof I have signed my name to this specification in the presence of two subscribing witnesses.

WILLIE A. BOYNTON.
